MOLD FOR CONCRETE STEPS

Colquit Peterson, Tampa, Fla.

Application December 17, 1945, Serial No. 635,442

3 Claims. (Cl. 25—118)

1

This invention relates to concrete molds and particularly to a concrete step mold adjustable for width and length.

The primary object of the invention is to provide longitudinally adjustable clamping means to hold the sheet metal front plate in close and rigid engagement with the end plates, to provide longitudinally adjustable means to hold the rear ends of the end wall plates at predetermined distances apart, and to provide readily operable clamping means to hold the inner wall members in parallel relation with the end plates.

In the drawings showing preferred forms of the devices selected for purpose of illustration, Figure 1 is a perspective view, seen from the rear, of an adjustable mold for a monolithic concrete step having integral supporting bar portions; Fig. 2 is an end elevation and Fig. 3 a plan view of the clamping means for the rear ends of the end plates and wall members between which the supporting bar portions are cast; and Figs. 4 and 5 are respectively a side elevation and a plan view of the longitudinally adjustable clamp connecting the front plate with an end plate.

A plank 1 supports the front plate 2, one edge of which is bent out as a base flange 3 and the other edge of which is formed with the nosing groove 4, the flange and the groove each extending the full length of the plate.

Slidable longitudinally of the plate from either end, are a pair of clamps 5, each consisting of a strap curved midway of its length as a central loop embracing and resting upon the metal forming the nosing groove, the ends of the strap extending as substantially parallel arms on opposite vertical faces of the plate 2. A boss 6 may be welded near the lower end of the front arm to provide additional thickness for a screw 7 engaging the plate 2 opposite a bracket 8 on the rear arm.

In the bracket 8 is pivoted a bolt 9 adapted for engagement within a notch 10 in a keeper 11 secured to an end wall member 12. A nut 13 on the bolt 9 serves to pull the side face of the front plate and the front edge of the end plate into rigid contact with each other. The upper curved portion of the clamp may be reinforced by a central flange or rib 14 welded centrally of the strap at the point incurring the greatest stresses.

The arrangement just described is duplicated at the other end of the step 16. The two end members 12 serve as the end walls for the tread portion of the concrete step 16 and the upper edge of each member 12 has a nosing groove formed therein of a length desired for the nosing

2

or trim at the end of the step. The metal forming this groove 17 is curved at its front end to fit closely within the groove 4 of the plate 2. To the rear of the groove 17, the plate 12 acts as the outer side wall of the mold portion for the adjacent supporting bar 18 cast at each end of the tread as an integral unit with the step. An inner wall member 19, similar to the members 12 except for the omission of the nosing groove portion, is set parallel with the adjacent member 12 at each end of the step at a distance fixed by an interposed spacer block 20. The front end of the members 19 are placed at the rear line of the tread portion of the step, and the blocks 20 are at a distance from the tread determined by the length of supporting bar desired. For the central supporting bar 21, when one is used, side wall members 22 will be set with their front ends in alignment with the front ends of the members 19 and a spacer block 20 will hold them at the right distance apart and act as a rear wall for the bar.

Between the rear ends of the wall members 12 and 19, and between the rear ends of the wall members 22 when these are used, are rear spacer blocks 23 of the same width as that of the blocks 20. On the rear face of each of the blocks 23 is an upper sleeve 24 in which is pivotally mounted a metallic rod 25 having both ends bent at about 80° to the axis of the sleeve forming diverging arms for engagement with tapering flanges 26 projecting outward from the outer face of each of the wall members between which the block 23 is set. The flanges 26 will be opposite each other and made with the same taper and at a relatively short distance from the sleeve 24 for simultaneous engagement with the clamping arms of the rod 25. As the arms are swung forward into engagement with the flanges, the wedging action will force the wall members into tight contact with the sides of the blocks 23, and because of the elasticity of the metal of the arms, the arms will spread enough to exert a constant inward pressure on the wall members. Between the block 20 and the block 23 in any of the spaces between the adjacent wall members, a spacing member 27 will be used to hold the block 20 and the block 23 at the desired distances apart, resisting any rearward pressure on the block 20.

Between the front end of the inner wall member 19 and the front end of the next wall member along the rear face of the tread 16 is placed a block 28 which acts as a rear wall for the portion of the step between two successive supporting bars. A single intermediate supporting bar 21

is shown in Fig. 1, and this will be sufficient for a reinforced step of any ordinary length. For unusually long steps two or more intermediate bars may be used or the intermediate bar may be omitted for shorter steps or for those sufficiently reinforced when an intermediate bar would be undesirable. In the absence of an intermediate bar 21, a single block 28 would extend from one wall member 19 to the other.

On each block 23, is a sleeve 29 to receive a connecting member shown as a pipe 30 which runs the whole length of the mold with a clamp screw in each sleeve for engagement with the pipe to hold the blocks 23 in proper longitudinal positions at the rear ends of the mold walls 12, 15, 19, and 22.

After the clamps 5 are adjusted to secure the front plate 2 to the front ends of the wall members 12 at the distance from each other for the length of tread to be molded, the blocks 20 are set in place for the length of supporting bars 18 and 21 and the blocks 23 set approximately opposite the blocks 20. The wall members 19 are placed against the blocks 20 and 23 and held by the arms 25 while the wall members 22 are set against their blocks 20 and 23, and the members 28 placed between the front ends of the wall members 19 and 22. The end blocks 23 are slid to bring the wall 12 at right angles to the front plate and clamped to the pipe 30 by the screws 31. The walls 22, 22, 30 will also usually be set at right angles to the plate 2. If the various members have been made of the right length, the whole mold assembly should be sufficiently rigid. The spacing members 27 may be of any material of proper length, since their only function is to hold the blocks 20 against rearward movement.

U. S. Patent No. 1,963,866, June 19, 1934, to Colquit Peterson, discloses the type of concrete steps for which the adjustable mold shown in U. S. Patent No. 2,255,480, September 9, 1941, to Connor and Peterson, is especially adapted. It will be seen that the assembly herein disclosed has all of the advantages of the mold of the previous patent. The means now used for clamping the front plate to the end walls is readily slidable along the plate and provides a secure fastening to hold the front plate from outward movement and to hold the end plates from sidewise movement along the front plate. The end of the screw 7 bears against the outer face of the plate 2 about midway of its height and the bolt 9 acts in line with the screw to draw the plate into close engagement with the vertical front edge of the side wall. The spacer blocks 23 are easily adjustable to hold the rear ends of the wall members in their proper places and the simple clamping means carried by the blocks are easy to use for temporary clamping of the wall members as well as

for holding them in their permanent adjusted positions.

It will be understood that the invention is not limited to the exact details of construction illustrated but that many changes in form, proportion, and relation of parts may be made without departure from the invention as claimed.

I claim:

1. An adjustable mold for monolithic portable steps comprising a front plate, end plates adjustable longitudinally of the front plate, and a clamp for each end plate having two arms, one to bear against the outer surface of the vertical wall of the front plate and having a screw to bear against the wall at about midway of its height, and the other arm having a bolt pivoted thereto for detachable engagement with the end plate and a nut on the bolt to draw and hold the end plate in tight engagement with the front plate.

2. An adjustable mold for monolithic portable steps having a tread, a riser, and rearwardly extending supporting bar portions, comprising a front member having a vertical portion forming the front wall of the tread and riser portion of the mold, end members mounted substantially at right angles to the front member and adjustable longitudinally thereof to determine the length of the step, a wall member connected with each of the end members and separated therefrom by a spacing member adjustable lengthwise of the wall and end members to provide relatively narrow mold portions for the supporting bars of the step, rear spacer blocks interposed between the rear ends of the end members and the adjacent wall members, clamping means on the rear spacer blocks movable to engage the ends of the wall members and end members to secure them to the blocks, and means on each end block to engage a connecting member adapted to hold the rear spacer blocks in the desired longitudinal positions at the rear of the mold.

3. A structure as in claim 2 having a clamp adjustable along the front member to a position adjacent to the front end of the end member and connected therewith to secure the members together against lateral and longitudinal movement.

COLQUIT PETERSON.
